CLAIM

The ornamental design for a pillow wrap, as shown and described.

DESCRIPTION

FIG. 1 is a perspective view of the pillow wrap showing my design thereof, the pillow wrap being used with a pillow and a tag;

FIG. 2 is a front view thereof;

FIG. 3 is a bottom view thereof;

FIG. 4 is a back view thereof;

FIG. 5 is a top view thereof;

FIG. 6 is a left side view thereof;

FIG. 7 is a right side view thereof;

FIG. 8 is a front thereof in a folded state; and,

FIG. 9 is a back view thereof in a folded state.

The broken lines in the drawing are for illustrative purposes only and form no part of the claimed design.
